UNITED STATES PATENT OFFICE.

ALBERT T. FLAVELL AND ENOCH HOLLAND, OF PHILADELPHIA, PENNSYLVANIA, ASSIGNEES TO CEDARBOOK KNITTING COMPANY, OF PHILADELPHIA, PENNSYLVANIA, A CORPORATION OF PENNSYLVANIA.

UNDERGARMENT.

Application filed July 30, 1927. Serial No. 209,482.

Our invention relates to undergarments of the type generally known as "union suits" and it has for its general object to provide a garment in which the crotch portion thereof 5 is reinforced and strengthened by the co-action of two overlying supplemental strips of fabric which are secured to the body portion of the said garment.

It also is an object of the invention to provide an undergarment of the character indicated in which the crotch is formed of two overlying strips of fabric connected with each other and to the body of a garment, and the opposite end portions of which at the 15 front and rear sides of the garment are overlapped and are secured in such cooperative relation to each other as to form openings which normally remain closed to protect and conceal the underneath portions of the body 20 of the wearer.

Other objects and advantages of the invention will be pointed out in the detailed description thereof which follows or will be apparent from such description.

25 In order that the invention may be readily understood and its practical advantages fully appreciated, reference should be had to the accompanying drawing in which we have illustrated one form of embodiment thereof.

30 In the drawing:

Fig. 1 is a view in front elevation of an undergarment embodying the invention;

Fig. 2 is a view in rear elevation of the garment, the upper portion thereof being broken 35 away;

Fig. 3 is a view in transverse section taken on the line 3—3 of Fig. 1;

Fig. 4 is a view in front elevation of the lower portion of the part which in the completed 40 garment constitutes the body portion thereof, the said view indicating certain of the steps employed in the process of manufacture; and

45 Figs. 5 and 6 are views in perspective of a couple of supplemental strips or members which are adapted to be secured to the portion shown in Fig. 4 in such manner that in the completed garment they cooperate to form the crotch thereof, and also in such manner that the opposite end portions thereof overlap 50 to form the front and rear portions of the said garment.

In one method of manufacturing the garment the body portion thereof is constructed of knitted fabric which is knit originally in

the form of a continuous tube of relatively 55 large transverse area and thereafter cut into proper lengths to provide garments of the desired length. Thereafter the tubular sections thus produced are slit as indicated by the full lines at 1 and by the dash lines at 2 60 in Fig. 4 of the drawing, the said slits being in opposed relation to each other. The upper portion of the tubular section employed is cut and shaped to form the arm holes 3 and the opening at 4 for the neck, but as the manner 65 of constructing the upper portion of the garment including the arm holes and neck constitutes no part of the present invention further reference thereto will not be made.

The supplemental strips 5 and 6 are secured to the edges of the slits 1 and 2 in a manner to form the crotch portion of the garment as well as to form overlapping portions at the front and rear sides of the completed 70 garment as is best illustrated, perhaps, in 75 Fig. 3 of the drawing. The strip 5 in the completed garment as constructed by us overlies the strip 6 and for purposes of description the said strips hereinafter will be referred to as front and rear strips respectively. 80

Each of the strips 5 and 6 includes or comprises pointed end portions 10 and 11 which in the completed garment overlie each other. The edges 12 and 13 of the strips or sections 5 and 6 respectively and the edge 14 of the 85 opening or slit 1 are secured together from about the point 16 to about the point 17. From the latter point to the point 18 only the edges 12 and 14 are fastened together, the corresponding portion of the edge 13 being left 90 free, as indicated at 18'. From the point 18 around to about the point 19 the edges 20 and 21 of the strips or sections 5 and 6 respectively and the edge 22 of the slit 1 are secured together, but from the point 19 to about the 95 point 23 only the edges 21 and 22 are secured together. The portion of the edge 20 between the points 19 and 23 is free as indicated at 24 in Figs. 1 and 3 of the drawing. From the point 23 to about the point 25 all three edges 100 20, 21 and 22 are secured together.

It will be apparent that openings are provided between the points 17 and 18 and between the points 19 and 23 and that within the region bounded by the said points the 105 pointed or tapered portions 10 and 11 of the strips 5 and 6 overlap each other. Thus, while an opening is provided in the front of

the garment such opening is normally closed so that the underneath portion of the body is completely and fully protected.

- 5 The portions of the edges of the supplemental strips or sections 5 and 6 having been secured to the portion or member 2 of the garment as above indicated and described, the lower portions of the edges 14 and 30 may be secured together by a row of stitching 31 (to form a leg 31') which row of stitching is continued to secure the remaining portion of the edge 12 to the remaining portion of the edge 30 along the line 32 to a point at or approximating the upper end of the edge 30.
- 10 15 The edge of the upper end of the strip 5 is secured by stitching along the line 34 to the back part of the body portion of the garment transversely and generally somewhat above the middle thereof as shown in Fig. 2.
- 20 25 The lower portions of the edges 22 and 35 are secured together by means of a row of stitching 36 which row of stitching is continued along the dash line 37 to secure the remaining portion of the edge 21 of the strip 6 to the remaining portion of the edge 35.

30 The edge of the upper end of the strip 6 is located underneath the rear side of the body portion of the garment in alignment with the upper edge of the strip 5 and is secured to the said body by means of a row of stitching at 38. It will be seen that the strips 5 and 6 are overlapped and extend somewhat in cross-wise relation to each other, as shown in Fig. 1, so that likelihood of gaping is avoided. Furthermore, the said strips are adapted to be secured together by means of a button as indicated at 40.

35 40 Although we have described the stitches along the lines 31, 32 as having been made prior to the formation of the stitches along the lines 36, 37 it will be understood that the stitching of the strips to the portion of the fabric constituting the body portion of the garment may be performed in any manner 45 and in any order as may be desired.

It will be seen that we have provided a construction in which the crotch portion of the garment is of relatively great strength and in

which the openings at the front and rear sides of the garment are formed by the overlapping portions of supplemental strips secured to the main body portion of the garment in the manner as described and in a way to prevent practically the accidental opening thereof. By means of our invention we are enabled to provide a construction of garment which may be worn with a maximum of comfort and a maximum of protection and which may be manufactured economically.

Having thus described our invention, what we claim and desire to secure by Letters Patent is:

An undergarment of the character described, comprising body and leg portions, the said body portion having front and rear openings, strips connected with the said body portion for closing said openings, one of said strips overlying the other and the front end portion of each of said strips being relatively narrow and tapered, and the said strips extending from the rear to the front of the garment, the lower portions thereof located between the legs of the said garment constituting the crotch portion of the garment, the opposite edges of the relatively narrow tapered front portions of said strips being secured to the opposite edges of the opening in the front of the garment, the connection of one edge of the underneath portion being interrupted for a short distance at one edge of the opening, so and the connection of the opposite edge of the outer relatively narrow tapered portion being interrupted for a short distance whereby two openings in opposed relation to each other at the opposite edges of the said overlying portions are provided, and one edge of the rear portion of one of said strips being secured to one edge of the rear opening and the opposite edge of the other of said strips being connected to the opposite edge of said opening, substantially as described.

In testimony that we claim the foregoing as our invention we have hereunto signed our names this 21st day of July, 1927.

ALBERT T. FLAVELL.
ENOCH HOLLAND.
